(57) **CLAIM**

The ornamental design for a head mounted device as shown and described.

DESCRIPTION

FIG. 1 is a front, right, and top perspective view of a head mounted device, showing our design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged detail view taken from Line 9 in FIG. 2.

The broken lines shown in the drawings are included for the purpose of illustrating portions of the head mounted device that form no part of the claimed design.

The dash-dot broken lines in FIGS. 2 and 9 define the bounds of the enlarged detail view of the head mounted device and form no part of the claimed design.
